UNITED STATES PATENT OFFICE.

FRANK F. FRAKES, OF COLUMBIA, TENNESSEE, ASSIGNOR OF ONE-HALF TO JOSEPH M. DEDMAN, OF COLUMBIA, TENNESSEE.

RENEWABLE FUSE-ATTACHMENT PLUG.

Application filed January 21, 1926. Serial No. 82,781.

The present invention relates to attachment plugs especially adapted for use in connection with electrical appliances to feed sockets and more particularly attachment plugs having renewable fuses.

An important object of the invention is to provide a novel and inexpensive means for automatically breaking the circuit to the appliance, should a short circuit occur which 10 would ordinarily burn out the wire or appliance.

A further object of the invention is the provision of a device of this character which will be readily repaired by persons 15 unfamiliar with mechanics, to the end that the socket may again be brought into service.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is a sectional view through an attachment plug constructed in accordance 30 with the invention.

Figure 2 is a sectional view through an attachment plug, after the fuse has been burned out.

Figure 3 is a sectional view taken on line 35 3-3 of Figure 1.

Figure 4 is a bottom plan view of the attachment cap.

Referring to the drawing in detail, the reference character 5 indicates the plug section of the attachment plug, and as shown, the same is provided with the usual metallic threaded end member 6 that cooperates with the threaded socket in which the plug is to be positioned, for securing the plug 45 within the socket.

Pairs of spring fingers 7 are provided in the plug section, and as illustrated by Figures 1 and 2, these fingers cooperate to grip the contact arms 8 that form a part of the 50 attachment cap 9 which constitutes the upper section of the plug.

Secured within the attachment cap 9 is a spring arm 10 which extends downwardly in parallel relation with the arms 8, and adjacent to one of the arms. The free end of 55 the arm 10 is adapted to be moved into engagement with the arm 8 adjacent thereto, there being provided a securing member 11 formed of suitable fusible material adapted to hold the arm 10 adjacent to the arm 8, 60 associated therewith, to the end that electric energy passing through the arm 8 will be directed to the arm 10 through the wire.

Wires 12 and 13 extend into the usual central opening of the attachment cap, one 65 of the wires being secured to the screw 14 that is employed for connecting the arm 10 to the cap, to the end that electric energy will be carried off through the wire 12, to the appliance which is connected with the 70 opposite end of the wires.

From the foregoing it will be seen that should a short circuit occur in the electric circuit and which would otherwise result in the burning out of the electric appliance 75 or wire, fuse member 11 will be burned allowing the arm 10 to spring outwardly away from the arm 8 as shown by Figures 2, thereby by breaking the circuit.

To renew the plug, it is only necessary to 80 disconnect the plug section and attachment cap, and move the arm 10 into close engagement with the arm 8 and place a fusible member over the arms to connect them.

I claim:—

In combination with a separable electric plug having pairs of spring fingers and substantially straight contact arms to be positioned between the spring fingers, a spring arm secured to one of the sections and arranged adjacent to one of the contact arms, a securing wire of fusible material for securing the spring arm to the contact arm, and said securing arm adapted to be slid over the free ends of the contact arm and 90 spring arm.

In testimony that I claim the foregoing as my own, I have hereto affixed my signature.

FRANK F. FRAKES.
